Primary Examiner — Natasha Vujcic(74) *Attorney, Agent, or Firm* — McGarry Bair PC(57) **CLAIM**

The ornamental design for a light kit as shown and described.

DESCRIPTION

FIG. 1 is a top perspective view of a light kit illustrating my new design in the environment of a light.

FIG. 2 is a top view of the light kit with the light environment removed for clarity.

FIG. 3 is a bottom view of the light kit of FIG. 2.

FIG. 4 is a front view of the light kit of FIG. 2.

FIG. 5 is a rear view of the light kit of FIG. 2.

FIG. 6 is a right-side view of the light kit of FIG. 2; and,

FIG. 7 is a left-side view of the light kit of FIG. 2.

Portions of the light are shown in broken lines. Portions shown in broken lines form no part of the claimed design. Portions of the light are shown with jagged broken lines which define an indeterminate length. The jagged broken lines form no part of the claimed design.
